Fig. 4. $\frac{5}{18, 23, 17}$ Fig. 5.

A technical line drawing of a curved metal plate, labeled 22. The plate has a central U-shaped cutout, labeled 23. On either side of this cutout are two flaps, each labeled 24. The flaps are hinged to the main plate, as indicated by a line connecting the main plate to the base of each flap. The entire assembly is shown in perspective, highlighting the curvature of the main plate and the depth of the cutout.

UNITED STATES PATENT OFFICE.

RALPH F. STOEFFLER, OF ST. LOUIS, MISSOURI.

DENTAL ATTACHMENT.

Application filed July 6, 1926. Serial No. 120,715.

My invention relates to improvements in attaching means for removable dentures.

An important object of the invention is to provide means whereby the stress and

strains applied to the denture are properly absorbed by a resilient element, and hence the abutment tooth is properly protected.

A further object of the invention is to provide means of the above mentioned char-

acter, so constructed that the stud element is properly held within the socket element, but may be removed therefrom when desired and also so constructed that the spring may be removed from the socket element.

Other objects and advantages of the invention, will be apparent during the course of the following description.

In the accompanying drawings, forming a part of this specification, and in which like numerals are employed to designate like parts throughout the same,

Figure 1 is a perspective view of a device embodying my invention, showing the same in use,

Figure 2 is a plan view of a denture showing my attaching means applied thereto,

Figure 3 is a longitudinal section taken on line 3—3 of Figure 2,

Figure 4 is an elevation of the outer side of the socket element,

Figure 5 is a transverse section taken on line 5—5 of Figure 4,

Figure 6 is a perspective view of the spring element,

Figure 7 is a perspective view of the stud element,

Figure 8 is a horizontal section taken on line 8—8 of Figure 4, and,

Figure 9 is a vertical section taken on line 9—9 of Figure 5.

In the drawings, wherein for the purpose of illustration, is shown a preferred embodiment of my invention, the numeral 10 designates abutment teeth, and 11 a removable denture.

Suitably secured to the opposite sides of the removable denture are rigid T-shaped stud elements 12, including a transverse head 13 and shank 14.

Each abutment tooth 10 is provided upon the side or face thereof adjacent to the denture 11 with a recess or cavity 15 receiving an inlay 16, in which is anchored or imbedded a socket element 17. This socket element

comprises an inner side wall 18 and an outer side wall 19, which are substantially parallel,

and a bottom 20. The outer side wall 19 is provided with a longitudinal opening 21, for the reception of the shank 14 of the stud element.

60

The numeral 22 designates a generally U-shaped spring, formed of resilient metal, and this spring includes an inner arm 23, and an outer arm 24, connected by a bottom portion 25, as shown. The inner arm 23 preferably tapers upwardly, while the outer arm 24 is provided with a slot 26, to register with the slot 21, for the passage of the shank 14. The bottom 25 of the spring is preferably tapered or beveled, at its ends, as shown at 27. The inner and outer arms 23 and 24 are longitudinally curved, and normally bulge inwardly, the bulging being more pronounced adjacent to the free ends of these arms. The inner side wall 18 of the socket element is provided with an internal recess 28, of suitable shape and size to receive the inner arm 23; the outer wall 19 is provided with an internal recess 29, to receive the outer arm 24 and the bottom 20 is provided with an internal recess to receive the bottom 25 of the spring. The recesses 28 and 29 form shoulders 30 and 31, engaging over the free ends of the arms 23 and 24. These shoulders prevent the spring element from being accidentally removed from within the socket element, when inserted therein. There are spaces 32, about the bottom 25 of the spring, whereby the spring may be forced into the same by the stud element, and to allow of sufficient space 90 for the limited movement of the spring. The inner side wall 18 is provided with a groove 33, cut therein and leading to a point behind and beneath the shoulder 30. The function of this groove is to provide a space for the insertion of the point of a pair of tweezers, which may be employed to engage with the arm 23, in the removal of the spring element from the socket element.

105

110

In the use of the device, as shown in Figure 1, the socket elements are carried by the abutment teeth 10, and the stud elements are carried by the denture 11. The elements 12 are inserted into the outer ends of the socket elements, and forced into the same, to the closed position, Figure 3. The opposite flat faces of the transverse head 13 contact with the arms 23 and 24 of the spring element, causing these arms to become substantially flat. The spring arms contact with the opposite flat faces of the head 13, throughout the major portion of its area, thereby afford-

ing a large area of contact. The recesses 28 and 29 are slightly deeper than the thickness of the spring arms 23 and 24 and these spring arms are adapted to be moved into these recesses. The stud element is, of course, slightly smaller than the interior of the socket element, and satisfactory results may be obtained by having a clearance between these parts of about .001 of an inch, between all portions of the stud element and the adjacent portions of the socket element. The spring element not only holds the stud element in the socket element, but will take up the strains imparted to the denture, and will prevent undue strains being transmitted to the abutment teeth. The arrangement is such that the denture may be removed for cleaning or the like, and the spring may also be removed.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

Having thus described my invention, I claim:—

30. 1. A fastening means for a removable denture, comprising a socket element to be secured to an abutment tooth or the like, said socket element having oppositely arranged substantially flat side walls, one side wall having a longitudinal slot, a stud element to be secured to a denture and embodying a substantially flat head for insertion within the socket element between the substantially flat side walls, and a generally U-shaped spring mounted within the socket element and embodying spaced arms, said arms being normally bowed and adapted to be substantially straightened out by engagement between the substantially flat head and substantially flat side walls, one arm of the spring having a longitudinal slot for co-action with the slot of the socket element.

50. 2. A fastening means for a removable denture, comprising a socket element to be secured to an abutment tooth or the like, said socket element having oppositely arranged substantially flat side walls, one side wall having a longitudinal slot, both side walls being provided with internal recesses affording shoulders, a generally U-shaped spring arranged within the socket element, said spring including arms which are longitudinally bowed, the ends of the arms engaging beneath said shoulders and the arms being adapted to be forced into the recesses, and a stud element comprising a substantially flat head to enter the socket element and to

be held within the generally U-shaped spring, the stud element also comprising a shank, one arm of the spring having a longitudinal slot for co-action with the slot of the socket element to receive the shank of the stud element.

3. A fastening means for a removable denture, comprising a socket element to be secured to an abutment tooth or the like, said socket element having oppositely arranged substantially flat side walls, one side wall having a longitudinal slot, both side walls having internal recesses affording shoulders, the side wall opposite the slotted side wall having a groove leading back of the shoulder thereof, a generally U-shaped spring arranged within the socket element and including curved arms, the ends of the arms engaging beneath said shoulders and the arms being adapted to enter the recesses, one arm having a slot for co-action with the slot of the socket element, and a stud element having a substantially flat head and a shank, the head being adapted for insertion into the socket element within the spring while the shank enters said slots.

4. A fastening means for a removable denture, comprising a socket element provided with a longitudinal slot, a generally U-shaped spring arranged within the socket element and including spaced arms extending longitudinally thereof, one arm having a longitudinal slot to co-act with the first named slot, and a stud element having a head for insertion into the socket element within the spring and a shank to enter said slot.

5. A fastening means for a denture comprising a generally flat socket element having oppositely arranged sides, one side being provided with a longitudinal slot, both sides being provided upon their inner faces with shoulders, the side opposite the slotted side being provided upon its inner face with a groove extending behind and below the shoulder of this side, a generally U-shaped spring adapted to be arranged within the socket element, said spring including spaced arms and a transverse portion connecting said arms, said transverse portion being arranged adjacent to the bottom of the socket element and the free ends of the arms having interlocking engagement beneath said shoulders, said groove permitting of the insertion of an implement behind the adjacent arm for the removal of the spring, and a stud element having a head for insertion within the socket element and the generally U-shaped spring and a shank to enter said slot.

In testimony whereof I affix my signature.
RALPH F. STOEFFLER.
